3 Claims. (Cl. 84—267)

This invention relates to new and useful improvements to attachments for guitars and has as its principal aim and object a means whereby a rhythm slap is obtained during the normal playing of the guitar by means of a pick.

Another object of this invention is to provide a device of the character herewithin described which can be utilized as a rhythm accompaniment, such rhythm normally being applied by a player using brushes on a snare drum.

A yet further object of this invention is to provide a device of the character herewithin described which is easily attached to existing guitars and which, furthermore, can be adjusted to increase or decrease the resultant rhythmic slap.

With the foregoing objects in view, and such other objects and advantages as will become apparent to those skilled in the art to which this invention relates as this specification proceeds, our invention consists essentially in the arrangement and construction of parts all as herein-after more particularly described, reference being had to the accompanying drawings in which:

FIGURE 1 is a top plan view of the device shown on the sounding board of a guitar.

FIGURE 2 is a view substantially along the lines 2—2 of FIGURE 1.

FIGURE 3 is a side elevation of the device.

In the drawings like characters of reference indicate corresponding parts in the different figures.

Proceeding therefore to describe this invention in detail, reference character 10 represents the front surface of a guitar to one side of the strings (in the pick guard area), one string 11 being shown.

The device collectively designated 12 is preferably made of plastic and comprises a base 13, sides 14, and a top plate 15 making a substantially rectangular, hollow enclosure.

Situated within the enclosure and secured by the end 16 thereof to the base 13 by adhesive or the like, is an elongated flexible plastic strip 17, the end 18 of which extends through the open side 19 of the enclosure and then extends upwardly as shown at 20. It will be noted that the strip is clear of the base 13 apart from the attaching end 16.

The resiliency of the strip 17 normally maintains it in the uppermost position but the actual position of the tip 21 with relation to the string 11 can be adjusted within limits by means of the adjustor 22. This adjustor 22 is mounted for partial rotation upon a pivot pin 23 and is substantially circular in construction when viewed in plan. However, an off-standing portion 24 engages the upper surface of the strip 17 so that by rotating the portion 24 in the direction of the double headed arrow 25, the position of the tip 21 is adjusted. The portion 26 of the ad-

2

justor 22 extending beyond the casing, provides for manipulation to rotate the portion 24 as hereinbefore described. A tension spring 27 surrounds the pivot pin 23 and maintains the adjustor 22 in the uppermost position as clearly shown in FIGURE 3. A stop 28 extends upwardly from the strip 17 adjacent the end 16 and limits the rotation of the adjustor in this direction.

In operation, the device is adhesively secured by the base 13 to the upper surface of the guitar 10 so that the tip 21 is approximately $\frac{1}{16}$ of an inch away from the string 11, which string incidentally is the E or first string.

As the guitar is played in open chords, the pick automatically strikes the tip 21 after passing over the strings, moving the strip 17 downwardly with a slapping action against the base 13 which in turn is transferred to the sound box of the guitar.

The sound is identical to a man playing brushes on a snare drum and is of particular advantage to singers who accompany themselves with open chords on a guitar. The device can be used for various types of picking, such as Johnny Cash, Doc Williams and Carter Family style etc.

Whether playing fox trots, waltzes, rock and roll tempo etc. the device automatically adjusts itself to the tempo providing the hand movement is constantly steady.

The adjustor 22 increases or decreases the volume of the rhythmic sound which is particularly useful when doing radio and TV broadcasts.

Since various modifications can be made in our invention as hereinabove described, and many apparently widely different embodiments of same made within the spirit and scope of the claims without departing from such spirit and scope, it is intended that all matter contained in the accompanying specification shall be interpreted as illustrative only and not in a limiting sense.

What we claim as our invention is:

1. An attachment for guitars adapted to be secured to the pick guard area of the front surface of the guitar adjacent the strings thereof; said attachment comprising in combination a hollow enclosure, and a flexible strip secured by one end within said enclosure, the other end of said strip extending through an apertured side of said enclosure adjacent the strings of said guitar, an upturned pick engaging portion formed on said other end, and positioned with respect to said strings so that the conventional pick strikes the said other end of said strip after said pick has passed over said strings.

2. The device according to claim 1 which includes means within said enclosure to adjust the limits of movement of said strip.

3. The device according to claim 2 in which said means includes an adjustor pivotally mounted for partial rotation within said casing, a portion of said adjustor extending beyond said casing, an off-standing portion extending from said adjustor and contacting the upper surface of said strip.
